(57) **CLAIM**

The ornamental design for a building wall end, as shown and described.

DESCRIPTION

FIG. 1 is a perspective view of a building wall end;

FIG. 2 is an end view thereof;

FIG. 3 is a side view thereof; and,

FIG. 4 is a front view thereof.

The dot-dash broken lines appearing in FIGS. 1, 3 and 4 depict a symbolic break in the article. The portion beyond the break lines forms no part of the claimed design.

1 Claim, 3 Drawing Sheets

FIG. 1

FIG. 2

FIG. 3

FIG. 4
